TWO-WAY TELEPHONE AND TELEGRAPH
SYSTEMJ. Ernest Smith, Jackson Heights, N. Y., assignor
to Radio Corporation of America, a corpora-
tion of Delaware

Application October 30, 1942, Serial No. 463,883

12 Claims. (Cl. 179—4)

This invention relates to two-way telephone and telegraph systems, and more particularly to a device for improving the transmission characteristics of a combined telephone and telegraph circuit. The improvements have for their principal object to minimize the effects of outside interference upon telephone and telegraph channels and to overcome the effect of a variable propagation constant.

In the past, where the line consisted of a twisted pair of conductors, it has been found that the received signal varies greatly with weather conditions, the influence of the earth's magnetic field, and induced noise interference. Where a telegraph signaling system is to be combined with a telephone circuit, it has been a common practice to terminate the transmission line at both ends by a transformer having a center-tap through which telegraph signals might be sent and received. The telegraph signals would thus be conveyed over the two conductors of the twisted pair the same as if they were a single conductor. The telegraph apparatus at each station would be grounded, thus completing the telegraph circuit. The telephone circuit was operated in a conventional manner, voice signals being induced on the individual conductors of the twisted pair in phase opposition. The difficulties encountered were not so much due to interference between the telephone circuit and the telegraph circuit, as they were due to unstable ground return effects such as might be produced by the earth's magnetic field. Furthermore, the efficiency of the telegraph circuit was limited by a high degree of attenuation of the received signals. The telegraph system was also subject to erroneous operation due to induced noise interference on the line.

Accordingly, it is an object of my invention to provide a two-way communication system having a twin conductor circuit over which telephone and telegraph signals may be transmitted simultaneously, and wherein the signal propagation shall be rendered relatively independent of outside influences.

It is another object of my invention to provide a system of the class described which overcomes the adverse effects of attenuation in a long line and which requires a minimum of terminal apparatus for accomplishing this result.

Other objects and advantages of my invention will be made apparent in the description to follow. This description is accompanied by a drawing, in which:

Fig. 1 shows in diagrammatic form a preferred

5 circuit arrangement including apparatus units which are suitably combined at a single station and rendered operable both for transmission and reception of telephone and telegraph signals; and

Fig. 2 shows a modified circuit arrangement. Referring to Fig. 1, I show therein a line 1 terminating in a transformer winding 2 which is inductively coupled to a winding 3 in the same transformer. A high-pass filter 4 is interposed between the transformer winding 3 and terminals 5 leading, say, to a telephone instrument having a microphone and an earphone. The characteristics of the filter 4 are preferably those which will pass speech signals above a frequency of 250 cycles and will effectually block any frequencies below 250 cycles. For telegraph signaling, a low-pass filter 6 may be used. This filter will preferably pass any frequency below 250 cycles.

10 The filters 4 and 6 are so designed that energy may be fed into them from either end. They will, therefore, be uniformly efficient for two-way communication work. So far as the transformer winding 3 is concerned, this is connected to the right hand terminals of filters 4 and 6 in parallel. The left hand terminals of filter 6 are branched. One branch leads to the input side of an amplifier limiter device 7 which is useful 15 for amplifying the received telegraph signals. The output side of the amplifier 7 is again branched and leads to two parallel-connected filters 8 and 9. Filter 8 has a high-pass characteristic for passing frequencies above 125 cycles, for example. Filter 9 has a low-pass characteristic and passes frequencies below 125 cycles, for example.

20 The telegraph signals to be transmitted and received will preferably be composed of two distinguishable frequencies. For the sake of illustration, the marking frequency is indicated as 150 cycles, while the spacing frequency may be 100 cycles. Accordingly, the marking frequency will be passed by filter 8 and after rectification 25 in the rectifier 10, the rectified energy may be caused to traverse one winding 11 of a polarized relay. The two windings 11 and 12 of this relay are terminated in a common ground connection. Winding 12 is fed with rectified energy through the rectifier 13 in the output circuit of filter 8.

25 The tongue 14 of the polarized relay cooperates with stationary contacts one of which may be dead, while the other contact 15 is fed with a positive potential from any suitable source. The relay tongue 14 may be connected to the respon-

sive means in a receiving printer 16. When a signaling current of marking frequency traverses the high-pass filter 8 and is rectified, it energizes the coil 11 in the polarized relay and causes the armature 14 to make contact with the stationary contact 15. In this manner a marking impulse is impressed upon the responsive means in the receiving printer 16. As is well known, such responsive means may consist of selectors suitable for causing the printer to record characters corresponding to a train of telegraph signals.

The various terminal apparatus units thus far described are used at either station for the reception of telegraph code signals. The transmitting apparatus is preferably the same at the two stations and will now be described.

A conventional code keyer 17 is indicated as having five movable contacts 19 for composition of the well-known five-unit code signals. Such signals may be delivered by a manually operated keyboard or by a perforated tape sensing device. The code keyer also comprises a so-called start-stop contactor 20 if desired. In place of the code keyer, as represented, a simple hand-operated telegraph key may be used, or more elaborate apparatus such as a synchronous signaling system may be adopted if desired, the same as in multiplex telegraphy. In any case, the signals as transmitted may be characterized by two frequencies, say of 150 cycles for marking impulses, and of 100 cycles for spacing impulses.

A relay 18 has its winding connected between ground and a conductor which is alternately fed by positive and negative impulses in accordance with the permutational setting of the five code contacts 19 against positive or negative stationary contacts in the keyer 17. In conventional stop-start five-unit code keyers, each five-unit code signal is always preceded by a spacing impulse and followed by a marking impulse. The start impulse is produced, therefore, by movement of the contact tongue 20 from its positive to its negative stationary contact in the keyer 17.

The tongue 21 of relay 18 responds to code keying by the unit 17 and thus feeds current of different frequencies to the output circuit 22. The marking and spacing frequencies are preferably derived from two separate oscillators 23 and 24, each connected to a respective one of the stationary contacts which are associated with the relay tongue 21. One output terminal in each of these oscillators may be grounded if desired.

The signals are composed by the keyer 17 and as characterized for mark and space by the oscillators 23 and 24 may be applied through a capacitor 25 to the input circuit of an amplifier 26. The output circuit for this amplifier is connected to a double-pole single-throw switch 27, this switch being closed when transmitting. The conductors 28 connect the upper terminals of switch 27 to the left hand terminals of the low-pass filter 6. These signals are, therefore, applied to the transformer winding 3, now operating as a primary, and they are thus coupled to the terminating transformer winding 2 in the line 1.

In place of the oscillators 23 and 24, it is apparent that I may if desired utilize a single oscillator, the tuning of which may be varied by a switching operation under control of the relay 18. In this way the invention may be carried out very simply by providing a certain fixed tuning for the closed tank circuit of the oscillator, and by switching on and off an added capacitance

or inductance. The switching operation may be performed by the relay 18 under control of the keyer 17.

In Fig. 2 I show the same two filters 4 and 6 which have already been described in connection with Fig. 1. In Fig. 2, however, the low pass filter 6 has one of its terminals grounded and the other terminal is connected to a center tap on the winding 2a. The telegraph signaling channel is such, therefore, that the signals are transmitted co-phasally over the two conductors of the line 1, and ground connections are required at both stations for the return circuit.

Since identical terminal equipment may be used at the two ends of the line, there is no need to describe other apparatus than merely that which exists for transmission and reception at one station. It is apparent also that for use of the telephone circuit, it is unnecessary to show the actual telephone equipment which would be employed, since that equipment may be of any conventional type.

While I have illustrated my invention and described its components and its mode of operation in accordance with only two exemplary embodiments, it is to be understood that I do not intend to be limited to the use of the equipment which is herein shown and described.

I claim:

1. In a communication system, a two-way station comprising simultaneously operable telephone and telegraph apparatus, a two-conductor line, a high-pass filter offering a low impedance to the useful frequency band of telephone signals, a low-pass filter offering a low impedance to the useful frequency band of telegraph signals, said filters having cut-off points which render the frequency bands for telephony and telegraphy substantially mutually exclusive, a telephone set coupled to said line through said high-pass filter, and telegraph signaling apparatus coupled to said line through said low pass filter, said telegraph signaling apparatus having frequency-characterizing means for distinguishing between the marking and spacing elements of outgoing code signals and frequency discriminating telegraph signal responsive means adapted and arranged to accept and translate incoming code signals.

2. A two-way communication station according to claim 1, wherein said frequency discriminating means includes filters the input terminals of which are parallel-connected, said filters having cut-off points which lie between the characteristic marking and spacing frequencies of the incoming code signals.

3. A two-way communication station according to claim 1, wherein said frequency discriminating means includes a high-pass filter for accepting the frequency of the marking code elements, and a low pass filter for accepting the frequency of the spacing code elements, the frequency bands passed by the last mentioned filters being mutually exclusive, and said responsive means including a polarized relay having opposing windings each in circuit with the output terminals of one of these filters respectively, and means for rectifying the alternating current output from these filters, thereby to energize said relay windings with rectified potentials.

4. A system for composite telephony and telegraphy over a twin-conductor circuit, said system comprising filter means for passing telephone frequencies and for excluding telegraphic tone signal frequencies, filter means for passing

said telegraphic tone signal frequencies and for excluding said telephone frequencies, the different said filter means having parallel connections which are commonly coupled to said circuit, a telegraph signal transmitter operable to characterize the marking and spacing code elements by generation of different tone frequencies appropriate thereto, a polarized receiving relay, and telegraph signal translating means including separate filter and rectifier means whereby incoming code signals having said tone frequency characterizations may be caused to actuate said polarized relay.

5. A system according to claim 4 and including two tone frequency oscillators in said transmitter, and keying means operable to deliver tone signals from said oscillators at alternate intervals corresponding to said marking and spacing code elements.

6. A composite telephone and telegraph system comprising a plurality of stations in each of which transmitting and receiving devices are coupled to a communication channel, the transmitting devices including separate telephone and telegraph instruments, and the receiving devices also including separate telephone and telegraph instruments, filter means appropriate to the circuits of said telephone instruments and arranged for two-way passing of voice frequencies between said telephone instruments and said channel, and other filter means appropriate to the circuits of said telegraph instruments and arranged for two-way passing of certain tone frequencies allocated to telegraph code signals, the frequency bands passed by the two said filter means being mutually exclusive, said telegraph transmitting instruments including tone-frequency generating means and a code keyer arranged to feed tone frequency energy of different predetermined frequencies from said generating means through said other filter means to said channel, and said telegraph receiving apparatus having frequency selective means and rectifiers for translating said certain tone frequencies into signaling code elements of marking and spacing significance.

7. A system in accordance with claim 6 and including an amplifier limiter device in circuit between said other filter means and said frequency selective means.

8. A system in accordance with claim 6 and including a switch for disconnecting said tone-frequency generating means from said other filter means during reception of telegraph signals from a remote station.

9. Apparatus for signaling by simultaneous te- 55

lephony and telegraphy, comprising a communication channel extending between two stations, telephone filter means at both stations for passing speech frequencies above a predetermined filter cut-off point to and from said channel, said filter means being reactively coupled to conductive elements in said channel, telegraph filter means at both stations for passing two tone frequencies which lie in a frequency band below said cut-off point, said telegraph filter means being interconnected through ground and through conductive elements in said channel, means at each station for generating and keying said tone frequencies, thereby to transmit intelligence, and translating means at each station arranged to accept incoming telegraph signals which are composed of marking and spacing elements differentiated by said tone frequencies, said translating means including frequency selective filters each of which is arranged to accept an appropriate one of said tone frequencies and to reject the other.

10. Apparatus according to claim 9 and including a transformer at each station, one winding in each transformer being terminally connected to said telephone filter means and the other winding being terminally connected to parallel conductors in said channel.

11. Apparatus according to claim 9 and including a transformer at each station, one winding in each transformer being connected across terminals at one end of each said telephone filter means, and the other winding in each transformer being center-tapped and being connected across two conductors in said channel, the center-tap being connected to a terminal at one end of the adjacent telegraph filter means, and a ground connection to the remaining terminal at the same end of said telegraph filter means.

12. The method of signaling by simultaneous 40 telephony and telegraphy over a given communication channel, and by using said channel as a two-way system, which method comprises restricting speech waves as communicated to and from said channel to a band of frequencies above 45 a predetermined filter cut-off point, restricting telegraph signals as communicated to and from said channel to two distinct tone frequency allocations both of which lie below said cut-off point, generating said tone frequencies to represent the marking and spacing connotations of signal code elements, and translating such signal code elements when received at a given station by filter discrimination between the two said tone frequencies.

J. ERNEST SMITH.
